UNITED STATES PATENT OFFICE.

JOSEPH R. SMITH, OF WATERBURY, CONNECTICUT, ASSIGNOR TO THE
WATERBURY BUTTON COMPANY, OF SAME PLACE.

DESIGN FOR BUTTONS.

Specification forming part of Design No. 8,384, dated June 8, 1875; application filed May 31, 1875.
[Term of Patent 3½ years.]

To all whom it may concern:

Be it known that I, JOSEPH R. SMITH, of Waterbury, in the county of New Haven and State of Connecticut, have invented a new Design for Button; and I do hereby declare the following, when taken in connection with the accompanying drawings and the letters of reference marked thereon, to be a full, clear, and exact description of the same, and which said drawings constitute part of this specification, and represent a face view.

This invention relates to a design for metallic buttons, the object being to give to the button an inlaid appearance; and it consists in a surface indicating an inlaid plaid, as shown in the accompanying illustration.

The surface generally is that known as "Moire Metalique." In the surface lines are produced, indicating a plaid, as shown in the accompanying illustration, and this feature constitutes the peculiar characteristic of this design.

I claim—

The design for button, as shown and described, consisting of a plaid moire-metalique surface, substantially as specified.

JOSEPH R. SMITH.
